UNITED STATES PATENT OFFICE

148,125

DESIGN FOR A BRACELET OR THE LIKE

Karl C. Augenstein, Cranston, R. I., assignor to
 Speidel Corporation, Providence, R. I., a corporation of Rhode Island

Application August 24, 1946, Serial No. 132,794

Term of patent 14 years

(Cl. D45—4)

To all whom it may concern:

Be it known that I, Karl C. Augenstein, a citizen of the United States, residing at Cranston, in the county of Providence and State of Rhode Island, have invented a new, original, and ornamental Design for Bracelet or the like, of which the following is a specification, reference being had to the accompanying drawing, forming part thereof.

In the drawing:

Fig. 1 is a plan view of a bracelet showing my new design, the links of the bracelet being contracted; and

Fig. 2 is a view similar to Fig. 1 but showing the links expanded.

Fig. 3 is an enlarged side elevation of the contracted bracelet.

I claim:

The ornamental design for a bracelet or the like, substantially as shown.

KARL C. AUGENSTEIN.
